UNITED STATES PATENT OFFICE.

EMIL BOMMER, OF BROOKLYN, NEW YORK.

SPRING-HINGE.

1,226,179.

Specification of Letters Patent.

Patented May 15, 1917.

Application filed July 23, 1915, Serial No. 41,470. Renewed March 19, 1917. Serial No. 155,949.

To all whom it may concern:

Be it known that I, EMIL BOMMER, a citizen of the United States, and a resident of the borough of Brooklyn, in the county of 5 Kings, city and State of New York, have invented certain new and useful Improvements in Spring-Hinges, of which the following is a specification.

This invention relates to improvements in 10 and relating to spring hinges, and more particularly to that type of spring hinge known as a vertical floor surface spring hinge, such for example as the devices shown in the patents issued to me on March 16th, 1915, 15 namely, No. 1,131,659 and No. 1,131,667, and has for its object to provide a hinge of this character which is positive in action and simple in construction, and which may be adjusted so as to make the tension of the 20 spring greater or less as desired. A further object is to provide in such a hinge improved extraneous means for making inoperative the spring action thereof while the door is in open position, such means being 25 adapted to automatically return to normal spring-acting position when the door is closed.

With these and other objects in view, my 30 invention is shown in the accompanying drawings and will be hereinafter more fully described with reference thereto and finally pointed out in the claims.

In the drawings,

Figure 1 is a side elevation of my improved hinge as applied to a swinging door, with parts broken away, and partly in section;

Fig. 2 is a perspective view of the hinge-frame;

Fig. 3 is a detail view of the central shaft or pintle;

Figs. 4 and 5 are sectional detail views of the upper and lower tension members;

Fig. 6 is a vertical sectional detail view;

Fig. 7 is a modified form of construction as applied to a swinging door, and wherein is incorporated means for making the spring action inoperative when desired;

Fig. 8 is a vertical sectional view thereof;

Fig. 9 is a perspective view of one of the operating parts;

Fig. 10 is a sectional view taken on the line 10—10 of Fig. 7;

Fig. 11 is a sectional view taken on the 55 line 11—11 of Fig. 7; and

Fig. 12 is a rear view of the hinge-frame with the cover-plate removed.

Similar reference characters indicate corresponding parts throughout the several figures of the drawings.

Referring to the drawings, and more particularly to Fig. 1 thereof, a hinge-frame 20 is provided, of rectangular design, preferably having the outer side thereof rounded, as at 21, and provided with an upwardly extending member 22 at the outer side thereof and an inwardly extending member 22^a at the lower side thereof, said extensions having screw holes 23 therein for securing the said frame to a suitable recess provided in 70 the corner of the door by means of screws 24. The upper and lower ends of the frame are preferably of circular formation, as at 25 and 26, and are provided with bearings 27 and 28, the said bearing 27 being provided with a flanged portion 29, Fig. 6, beneath which are disposed antifriction balls 30. A central shaft or spindle 31 is journaled in the said bearings, said spindle being provided with enlarged ends 32 and 33, the 80 end 32 being preferably provided with a rounded upper surface 32^a for retaining the antifriction balls 30 within the said flanged portion 29. The lower end of the enlarged portion 33 is squared, as at 34, and the said 85 squared portion rests within a correspondingly shaped socket 35 secured to the floor, thereby retaining the said spindle in stationary position, and preventing movement of the same with the swinging of the door. 90

Arcuate recesses 36 and 37 are provided in the said enlarged ends 32 and 33 respectively of the spindle, each of the said arcuate recesses extending about half-way around the said enlarged portions, and being about 95 diametrically opposed to each other. A collar 38 is arranged on the enlarged end 32, and is provided with a flanged portion 39 having a plurality of radial openings 40 extending therethrough, and is also provided 100 with an opening 41 extending through the said flange and at right angles to the openings 40, and in which is disposed the upper end of a helical spring 42. A similar collar 43 is provided on the enlarged end 33, and 105 having a flanged portion 44, in which is arranged a single radial opening 45 and an opening 46 at right angles thereto, in which is disposed the other end of the said spring 42. A pin 47 is provided in the said collar 110

43, extending through the opening 45 thereof, and into the arcuate recess 37 of the spindle. The outer end of the said pin extends outwardly from the said collar, and is adapted to abut against the transverse face 48 of a projection 49 provided at the lower end of the frame 20, the opposite side of the said projection being beveled, as at 49^a.

A pin 50 is also provided in the collar 38, 10 extending through one of the openings 40 thereof, and into the arcuate recess 36 at the upper end of the spindle 31, the outer end of the said pin abutting against the transverse face 51 of a projection 52 provided at the 15 upper end of the said frame, the opposite face of the projection being beveled, as at 51^a, but the bevel being oppositely disposed to the bevel of 49^a. It will be seen that by changing the pin 50 from one of the openings 40 to another, that the tension of the spring 42 may be made greater or less as desired. At the upper end of the door, there is preferably provided a socket 20^a, in which is disposed a preferably spring-pressed 25 plunger 20^b of the door frame for pivotally holding the upper end of the door in position.

In swinging of the door, the operation of this embodiment of my improved hinge is as follows:—

When the door is swung to the right for instance, the pin 47 at the lower end of the spindle 31, which pin 47 abuts against one end of the arcuate recess 37 and against the lower projection 49 of the hinge-frame 20, permits the movement of the collar 43 with the door. The lower projection 49 forces the collar 43 to rotate about the lower end of the spindle 31 by means of the pin 47, which is free to move in this direction in the arcuate recess 37 to the other end thereof. The upper projection 51 is moved away from the pin 50; the spring is thereby tensioned, and when the door is released, it returns the same to normal or closed position. When the door is opened in the other direction, however, the action is reversed, the upper collar 41 in this case moving with the hinge-frame, by reason of the pin 50 abutting against one end of the recess 36, the pin 50 being free to move in the recess 36 to the other end thereof, the collar 38 rotating about the upper end of the spindle by means of the projection 51 abutting against the pin 50 and moving the same with the hinge-frame. The lower projection 48 is moved away from the pin 47.

In Fig. 7, I have shown a modified form of my invention, in which means are incorporated for making the spring inoperative when it is desired to have the door remain in open position. In this construction, a frame 53 is provided similar in shape to the frame 20 of the foregoing construction, and having bearings 54 and 55 at the upper and

lower ends thereof, in which are journaled the ends of a central spindle or shaft 56. The intermediate portion 57 of the said shaft is smaller in diameter than the ends thereof, in order to prevent unnecessary friction, and the lower end engaging the bearing 55 is enlarged, as at 58, and is provided with a squared downwardly extending portion 59, which engages a correspondingly squared socket 59^a secured to the floor, thereby preventing movement of the said shaft with the swinging of the door. A sleeve 60 is mounted on the spindle 56, resting at its lower end on the shoulder 61 formed by the enlarged portion 58, and a flange 62 is provided at the upper end thereof, and the intermediate portion is recessed as at 63. At the lower end of the sleeve, an arcuate cut-out portion 64 is provided extending preferably about half-way around the same.

Beneath the flange 62 is provided an arcuate recess 65 also extending preferably about half-way around the sleeve, but about diametrically opposed to the said cut-out portion 64. A collar 66 is provided at the upper end of the sleeve 60, having a flange 67 fitting beneath the flange 62 of the said sleeve, the said flange 67 being provided with a plurality of radial openings 68 extending therethrough, and also with an opening 69 at right angles to the openings 68, and in which is disposed the upper end of a helical spring 70. A similar collar 71 is provided at the lower end of the sleeve, having a flange 72, which rests upon the lower portion of the hinge-frame, said flange being provided with a single radial opening 73 and an opening 74 at right angles thereto, in which is disposed the other end of the said helical spring 70.

A pin 75 is provided in the collar 71, extending through the said opening 73 and into the arcuate cut-out portion 64 of the sleeve, the outer end abutting against the transverse face of a projection 76 provided at the lower end of the hinge-frame. A pin 77 is also provided in the collar 66 extending through one of the openings 68 thereof and into the arcuate recess 65 of the said sleeve, the outer end thereof abutting against the transverse face of a projection 78 provided at the upper end of the hinge-frame, the projection 78 being oppositely disposed from the said projection 76.

Keyed to the upper end of the spindle 56 by means of a pin 79 is a locking member 80, which overhangs at its forward portion the flange 62 of the sleeve 60, and in this overhanging portion there is provided a hole 81, in which is disposed a spring-pressed plunger 82, which engages a recess 82^a provided in the periphery of the flange 62, and rests against the upper surface of the collar 66. A portion of the plunger, however, overhangs the collar 67. A for-

wardly extending member 83, provided on a plate 84 disposed within a suitably shaped recess 85 of the hinge-frame, which plate is balanced in its seat so as to rock forward by gravity aided by a secondary action of the spring 94, Fig. 12, which tends to push the plate 84 with its forwardly extending member 83 forward into proper contacting position with the plunger 82, is disposed beneath the said plunger and is movable upward and downward within a slot 86 for lifting the same.

For enabling the operation of this lifting member, a second plate 87, upon the upper edge of which the lower edge of the balanced lifting plate 84 movably rests, is disposed beneath the said plate 84, and is provided with a forwardly extending wedge-shaped projection 88, which is movable within a slot 89 of the frame. The plate 84 is provided at its lower end with a forwardly extending projection 84^a to form a forwardly extending seat for the lower end of the spring 94, Fig. 12.

Pivoted to the said frame beneath the projection 88 are two pivoted levers 90 and 91 extending at each side of the hinge and provided with inclined surfaces 92 and 93, which engage the inclined faces of the wedge-shaped projection 88, and upon depression of either of the said levers, will cause the said projection and the plate 87 to be lifted, thereby lifting the upper plate 84 and the projection 83 carried thereby, which causes the plunger 82 to be forced into the hole 81, whereupon the door may be operated without spring power, and the plunger will be carried out of register with the recess 82^a of the flange 62 and will engage the upper surface of the flange 62, thereby permitting the collars 66 and 71 to be moved with the door in either direction, and causing the spring to be inoperative during this movement. It will be seen that upon closing of the door, the plunger 82 will again engage the recess 82^a of the flange 62, thereby locking the same to the member 80 and to the spindle 56, and causing the spring to again be operative. For returning the lifting member to its normal position, a spring 94, Fig. 12, is provided within a recess 95 of the member 84, and engages at its upper end a projection 96 of the recessed portion 85 of the frame, and engages at its lower end a forwardly extending projection 84^a of the member 84.

A cover plate 97 is secured over the said recess 85 for holding the parts of the lifting mechanism in position, said plate being preferably provided at its lower end with two downwardly extending projections 98 and 99, which engage corresponding recesses 100 and 101 in the hinge-frame, and the upper end thereof is preferably provided with a hole 102, through which a fastening

screw 103 may be secured to the frame. The spring 94 also serves to press the plate 84 with its member 83 forward into contact position with the plunger 82, the lower edge of plate 84 having a forward projection 84^a 70 to seat the lower end of the spring 94 thereon somewhat forward of its upper end.

The operation of this form of my improved hinge, excepting the spring-actuated plunger 82 for connecting and disconnecting the coil spring 70 and the mechanism actuating said plunger 82 above described, is exactly the same as that described with reference to the first embodiment when the spring is in operative position, the sleeve 80 60 when locked to the shaft or spindle 56 performing the same function as the shaft 31 of the first embodiment.

I have illustrated preferred and satisfactory forms of my invention, but it is obvious that changes may be made therein within the spirit and scope thereof, so that I do not desire to be limited to the form shown, except as may be required by the appended claims.

I claim:—

1. In a spring hinge of the character described, the combination with a frame mortised in the door, comprising spaced inner and outer walls, spaced upper and lower walls, provided with bearings, and oppositely disposed stops at the upper and lower ends of said frame, of a stationary shaft journaled in said bearings, and provided at the upper and lower ends thereof with oppositely disposed arcuate slots, rotatable members on the upper and lower ends of the said shaft at the slotted portions thereof, and pins radially disposed in said rotatable members having their ends extending beyond the inner and outer surfaces thereof, engaging at the inner ends the said arcuate slots of the shaft, and at the outer ends the said oppositely disposed stops of the frame, one of said rotatable members 95 adapted to be rotated by one of said stops during one direction of movement of the door, the other of said rotatable members to be rotated by the other of said stops during the other direction of movement of the door, 100 the ends of the pins engaging the said oppositely disposed slots, adapted to prevent movement of the non-rotating member with respect to the shaft by engaging the ends of the said oppositely disposed slots. 115

2. In a spring hinge of the character described, the combination with a frame mortised in the door, comprising spaced inner and outer walls, spaced upper and lower walls provided with bearings and oppositely 125 disposed stops at the upper and lower ends of said frame, of a stationary shaft journaled in said bearings and provided with enlarged upper and lower ends, having oppositely disposed arcuate slots, therein, the 130

walls of the said slots being entirely closed, rotatable members on the upper and lower ends of the said shaft at the slotted portions thereof, and pins radially disposed in said rotatable members having their ends extending beyond the inner and outer surfaces thereof, engaging at the inner ends the said arcuate slots of the shaft, and at the outer ends the said oppositely disposed 10 stops of the frame, one of said rotatable members adapted to be rotated by one of said stops during one direction of movement of the door, the other of said rotatable members adapted to be rotated by the other of said stops during the other direction of movement of the door, the ends of the pins engaging the said oppositely disposed slots, adapted to prevent movement of the non-rotating member with respect to the shaft by 15 engaging the ends of the said oppositely disposed slots.

3. In a spring hinge of the character described, the combination with a frame mortised in the door, comprising spaced inner and outer walls, spaced upper and lower walls provided with bearings, and oppositely disposed stops at the upper and lower ends of said frame, of a stationary shaft journaled in said bearings, a sleeve on said shaft, rotatable means on the upper and lower ends of said sleeve, a spring disposed between said rotatable means, means on said sleeve adapted to permit movement of one of said rotatable means in one direction with respect thereto, means on said sleeve adapted to permit movement of the other of said rotatable means in the other direction, means on the said rotatable means adapted to be engaged by said oppositely disposed stops of the frame, to rotate one 20 of said rotatable means during one direction of movement of the door, and to rotate the other of said means during the other direction of movement, and releasable means adapted to lock the said sleeve with respect to the said shaft.

4. In a spring hinge of the character described, the combination with a frame mortised in the door, comprising spaced inner and outer walls, spaced upper and lower walls provided with bearings, and oppositely disposed stops at the upper and lower ends of said frame, of a stationary shaft journaled in said bearings, a sleeve on said shaft provided at its upper end with a flanged rim, rotatable means on the upper and lower ends of said sleeve, a spring disposed between the said rotatable means, means on the said sleeve adapted to permit movement of one of said rotatable means in one direction with respect thereto, means on said sleeve adapted to permit movement of the other of said rotatable means in the other direction, means on said rotatable means adapted to be engaged by the said 25 means.

oppositely disposed stops of the frame, to rotate one of said rotatable means during one direction of movement of the door, and to rotate the other of said means during the other direction of movement, locking means 70 carried by the said shaft provided with means adapted to engage the said flange of the sleeve to lock the said sleeve with respect to the said shaft, and extraneous means adapted to disengage the said means from the said flange to permit independent movement of the sleeve.

5. In a spring hinge of the character described, the combination with a frame mortised in the door, comprising spaced inner and outer walls, spaced upper and lower walls provided with bearings, and oppositely disposed stops at the upper and lower ends of said frame, of a stationary shaft journaled in said bearings, a sleeve on said shaft provided at its upper end with a flanged rim, rotatable means on the upper and lower ends of said sleeve, a spring disposed between the said rotatable means, means on the said sleeve adapted to permit movement of one of said rotatable means in one direction with respect thereto, means on said sleeve adapted to permit movement of the other of said rotatable means in the other direction, means on said rotatable means adapted to be engaged by the said oppositely disposed stops of the frame, to rotate one of said rotatable means during one direction of movement of the door, and to rotate the other of said means during the other direction of movement, locking means 80 carried by the said shaft provided with means adapted to engage the said flange of the sleeve to lock the said sleeve with respect to the said shaft, and extraneous means adapted to disengage the said means from the said flange to permit independent movement of the sleeve.

6. In a spring hinge, the combination with a spring actuated door closing member and means adapted to be actuated to make the same inoperative, of means for actuating the said first-named means, comprising a recessed member, the upper portion of the recess thereof being tapered inwardly, and a plate having a projection thereon, and adapted to be moved in said recess and oscillated forwardly in the said recess to enable the said projection thereof to engage the said first-named means.

7. In a spring hinge, the combination with a spring actuated door closing member, and means adapted to be actuated to make the same inoperative, of means for actuating the said first-named means, comprising a recessed member, the upper por- 125

- tion of the recess theréof being tapered inwardly, a plate adapted to be moved in said recess and oscillated forwardly in the said recess, and a spring in said recess disposed to one side of the vertical axis of said plate, the forward pressing secondary action of the said spring adapted to push the said plate and the projection thereof forward into contact with the said first-named means.
8. In a spring hinge, the combination with a spring actuated door closing member, and means adapted to be actuated to make the same inoperative, of means for actuating the said first-named means, comprising a recessed member, the upper portion of the recess thereof being tapered inwardly, a plate adapted to be moved in said recess and oscillated forwardly in the said recess, and a spring in said recess disposed to one side of the vertical axis of said plate, and a projection within said recess at the bottom edge of the said plate adapted to seat the lower end of the said spring forward of the center of the vertical axis of the said plate, to cause the forward pressing secondary action of said spring to hold the said plate and the projection thereof at all times in contact position with said first-named means.
9. In a spring hinge, the combination with a spring actuated door closing member, and means adapted to be actuated to make the same inoperative, of means for actuating the said first-named means, comprising a divided slide plate adapted to be moved to engage the said first-named means.
10. In a spring hinge, the combination with a spring actuated door closing member,

and means adapted to be actuated to make the same inoperative, of means for actuating the said first-named means, comprising a divided slide plate, one part thereof having a rocking motion forward upon the other part thereof, and adapted to be moved to engage the said first-named means.

11. In a spring hinge, the combination with a spring actuated door closing member, and means adapted to be actuated to make the same inoperative, of means for actuating the said first-named means, comprising a recessed member having slots therein, and a divided slide plate disposed in said recessed member, and operating means provided on said slide plate extending through said slots and adapted to be actuated to engage the said first-named means.

12. In a spring hinge, the combination with a spring actuated door closing member, and means adapted to be actuated to make the same inoperative, of means for actuating the said first-named means, comprising a recessed member, the upper portion of said recess being tapered, a divided slide plate disposed in said recess, the upper portion of said slide plate being tapered to permit a forward rocking movement thereof upon the lower portion of the said slide plate, and adapted to engage the said first-named means.

In testimony that I claim the foregoing as my invention, I have signed my name in presence of two subscribing witnesses.

EMIL BOMMER.
